UNITED STATES PATENT OFFICE.

ANDREW G. SNYDER, OF PIQUA, OHIO.

MACHINE FOR BENDING SHAFTS.

SPECIFICATION forming part of Letters Patent No. 309,579, dated December 23, 1884.

Application filed July 5, 1884. (No model.)

To all whom it may concern:

Be it known that I, ANDREW G. SNYDER, a citizen of the United States, residing at Piqua, in the county of Miami and State of Ohio, have 5 invented certain new and useful Improvements in Machines for Bending Shafts, of which the following is a full, clear, and exact description, reference being had to the accompanying drawings, forming a part of this specification.

The object of my invention is the application to this class of machines of automatic power-bending mechanism, whereby the operation of bending can be accomplished more 15 certainly and speedily, and without the employment of manual labor, as heretofore.

The novelty consists in the construction, arrangement, and combinations of the parts, as will be hereinafter set forth and specifically 20 claimed.

In the accompanying drawings, Figure 1, Sheet 1, is a side elevation of a shaft-bending machine embodying my invention. Fig. 2, Sheet 1, is a plan view of one end of the table, 25 showing the relative positions of the parts just before the bending is commenced. Fig. 3, Sheet 2, is a plan view of the entire table just after the bending has been completed.

The same letters of reference are used to indicate corresponding parts in all the figures.

The construction of the table and formers, with the exceptions hereinafter pointed out, may be substantially the same as that shown and described in my Reissued Patent No. 35 9,773, of June 21, 1881, and I will only describe them here by saying that A is the bed of the table, B the removable plate attached thereto, C the stationary center former, and D the endwise movable former, which is operated by the hand-screw E.

F is a strap surrounding the former D, and having attached to its ends the angular hinged abutments G, against which the ends of the pair of shafts H are placed, as seen in Fig. 2. 45 The hinged abutments G, whose pivots are at a, are secured to the swinging outside or wing formers, I, as shown.

J is any power or line shaft carrying pulleys K L, from which belts M N pass to pulleys O P upon a counter-shaft, Q, suitably journaled beneath the table. The shaft Q also

carries two small pinions, R S, which mesh, respectively, with two larger pinions, T U, upon a shaft, V. Upon the outer ends of this shaft V are beveled pinions W, which mesh with beveled pinions Y upon two vertical shafts, A', which, passing up through suitable bearings in the table, have keyed or otherwise rigidly secured to their upper ends horizontal arms B', to the upper outer ends of which are 55 journaled rollers C' on line with and adapted to operate the swinging formers I.

D' E' are two foot-pedals pivoted at b, and whose bent lower ends carry small idler-pulleys F' G' in close proximity to the belts M 65 and N, respectively. These belts M and N are normally slack and hang loose upon the pulleys K L, so that the pulleys O P are not revolved by them. Now, supposing a pair of shafts be placed upon the table, as seen in Fig. 2, and bent to the former C by the clamps H', operated by the right and left screws I', and held down by the cross-bar J', as shown in Fig. 3, the operation of bending the tips by the power mechanism is as follows: The 70 operator presses down the treadle D', which, taking up the slack of the belt M, causes the revolution of the pulley O and shaft Q, and, through the medium of the pinions R, T, W, and Y, and shafts A', causes the arms B' to 75 turn toward the formers I until the rollers C', coming in contact therewith, force them inward, and thereby bend the shafts to the position shown in Fig. 3, at which time the treadle D' is released and the movement of the parts 80 stopped. To bring back the arms B' to their starting-point, the operator presses down the treadle E', which, acting upon the belt N, reverses the former motion of the shaft Q and its connections, thereby causing the arms B' to be 85 again swung out to the position shown in Fig. 2. Of course it is understood that a large number of formers, all fitting to the table, may be employed, and that after the bending operation 90 has been completed the usual clamps are applied to lock the parts together, so that the whole may be removed from the table to be dried or seasoned, and that after one set has been bent to the formers it is removed and a set which has been dried or seasoned is replaced 95 upon the table, the finished shafts removed, and new ones placed in position to be bent, thus en-

abling the operation of bending to be continuous, if desired.

The next feature of my present invention consists in the power mechanism for giving the bend to the butts of the shafts, which can be done before or after, or simultaneously with the bending of the tips. As before stated, the shafts are clamped to the center former, C, are locked down by the cross-bar J' and by 10 wedges c, as in my patent before referred to. The ends of the butts rest in the abutments d, attached to straps e, whose rear ends are suitably hooked, as at f, to the plate B.

Beneath the straps e are coincident straps 15 g, secured at their rear ends to the table in any suitable manner, and at their forward ends to angular abutments h, attached to or forming part of a segment-frame, K', the essentials of which are that it should have the 20 two segment-formers i, Figs. 1 and 3, and an operating-arm, j, which, when the machine is at rest, or before the bending operation is commenced, occupies the position shown in Fig. 1. Suitably journaled beneath this end of the 25 table is a shaft, L', carrying at its ends, so as to clear the sides of the table, two arms, k, which, when the machine is not in operation, may rest upon a horse, M'.

Connecting the outer ends of the arms k 30 is a pivoted cross-piece, l, carrying at or about its middle two friction-rollers, m, which loosely embrace the arm j, as shown in Fig. 1. Also keyed upon the shaft L' is a worm-wheel, N', with which engages a worm, O', upon a horizontal shaft, P', carrying two loose pulleys, Q' R', with clutch mechanisms S' T', of any suitable construction, to enable either pulley to be locked to the shaft at will. In this instance it is done by the sliding feathered hub U' upon 40 the shaft P', which is operated by any suitable lever or handle, V'. Belts n o connect the pulleys R' Q', respectively, to the pulleys p q upon a power or line shaft, r. As will be observed, the belt o is crossed, so that the pulleys 45 R' Q' may have reversed revolutions. Now, from this construction it will be seen that when a pair of shafts are clamped upon the table, as before described, and are ready to be bent at their butts, the operator, by means 50 of the lever V', locks the pulley R' to the shaft P', whereupon the arms k are raised, and, acting upon the arm j, turn up the segment-benders i until the parts assume the position shown by the light dotted lines in Fig. 1, at which 55 point the bending of the shafts commences. The segment-benders continue to roll over until the position of parts shown by the heavy dotted lines is reached, at which time the shafts will be bent up, as indicated, and are 60 locked up by means of links or other suitable means, s. (Indicated by dotted lines in Fig. 1.) By now unlocking the pulley R', and by locking the pulley Q' to the shaft P', the motion of the arms k is reversed and the segment-bender brought back to its normal position. 65 In this manner shafts can be speedily and ef-

fectively bent without the exertion of manual labor, and without danger of buckling or warping them.

Having thus fully described my invention, 70 I claim—

1. The combination, in a shaft-bending machine, of a suitable supporting frame or table, a central former carried thereby, and curved as described, arms located one at each side of 75 said former, and each mounted on a shaft suitably journaled, a wheel mounted on said shaft, and driving devices gearing with said wheel to rotate the said shaft and automatically swing said arms in the direction of the former, substantially as set forth. 80

2. The combination, in a shaft-bending machine, of a suitable supporting frame or table, devices for securing the shafts thereon, segmental benders located at one end of said table 85 adjacent to the butts of said shafts, and adapted to engage the extremities of said butt portions, arms attached to said segmental benders, a shaft suitably journaled, an arm connected thereto and to the bender-arm, and devices 90 driving said shaft to move the first-mentioned arm, substantially as and for the purpose set forth.

3. The combination, in a shaft-bending machine, of a suitable supporting frame or table, 95 a central former arranged thereon, and curved as described, a strap, F, secured to said former, abutments G, hinged to said strap, and adapted to receive the forward ends of the shafts, wing-formers pivotally secured to said 100 abutments, arms located one at each outer side of said wing-formers, and each mounted on a shaft suitably journaled, a wheel mounted on said shaft, and driving devices gearing with said wheel to revolve the shaft and swing 105 the arms in the direction of the wing-formers, substantially as set forth.

4. The combination, in a shaft-bending machine, of a suitable frame or table, a central former carried thereby, and curved as described, arms B', pivoted at each side of said former, rollers C', journaled on said arms, wing-formers pivotally secured between said central former and said arms, and devices for automatically moving said arms to cause said 110 rollers to contact with said wing-formers, substantially as set forth.

5. The combination, in a shaft-bending machine, of a suitable frame or table, a central former carried thereby, and curved as described, an arm located one on each side of said former and mounted on a shaft suitably journaled, a wheel carried by said shaft, driving devices gearing with said wheel to rotate the same and its shaft, for the purpose specified, and appliances for reversing the rotation of said wheel and shaft, substantially as set forth. 120

6. The combination, in a shaft-bending machine, of a suitable supporting frame or table, 125 devices for securing the shafts thereon, segmental benders located at one end of said table

adjacent to the butts of said shafts, and straps bent to receive the extremities of said butt portions, arms attached to said segmental benders, a shaft suitably journaled, an arm 5 connected thereto and to the bender-arm, devices for driving said shaft to move the segmental benders, and appliances for reversing the movement of said segmental benders, substantially as set forth.

10 7. The combination, in a shaft-bending machine, of a supporting frame or table, means for securing the shafts thereon, straps *e*, at-

tached to said table, and carrying the abutments *d*, adapted to receive the butt portions of the shafts, straps *g*, located beneath the said straps *e*, segmental benders connected to the said straps *g*, and means for moving said benders to cause them to bear upon and vertically bend said shafts, substantially as set forth. 15
